UNITED STATES PATENT OFFICE.

ROBERT W. DAVIS AND DANIEL DAVIS, OF ELMIRA, NEW YORK, ASSIGNORS
TO THE DAVIS IMPROVED WROUGHT IRON WAGON WHEEL COMPANY,
OF SAME PLACE.

WHEEL-HUB.

SPECIFICATION forming part of Letters Patent No. 251,840, dated January 3, 1882.

Application filed November 15, 1881. (No model.)

To all whom it may concern:

Be it known that we, ROBERT W. DAVIS and DANIEL DAVIS, citizens of the United States, residing at Elmira, in the county of Chemung 5 and State of New York, have invented certain new and useful Improvements in Wheel-Hubs; and we do hereby declare that the following is a full, clear, and exact description of the same, reference being had to the annexed drawings, 10 making a part of this specification, and to the letters and figures of reference marked thereon.

Figure 1 of the drawings is a longitudinal central section of our invention; Fig. 2, an inner plan view of one of the clamping-plates, 15 showing the spokes in position. Fig. 3 is a similar view of the second clamping-plate; Fig. 4, a detail view of one of the spokes; and Fig. 5 is a vertical transverse section, in detail, taken through the clamping-plates and spokes.

20 The present invention has relation to certain new and useful improvements in the manner of securing metal spokes to the hubs of wheels; and the object thereof is to provide means whereby all the pressure is thrown against the 25 ribs at the center of the spokes and does not touch the edges thereof until it reaches their extreme end next to the axle-box, thereby preventing crystallization at that point by allowing the vibration to extend down into the hub. 30 These objects we attain by the construction substantially as shown in the drawings and hereinafter described.

In the accompanying drawings, A represents the axle-box, of the usual construction, 35 having at one end an annular flange, *a*, and at its opposite end screw-threads *b*, for the reception of a screw cap or nut, B. Around this axle box A are located two shells or hollow metal sections, C D, which together form the 40 outer portion of the hub or body thereof. The section C has an annular shoulder, *c*, against which abuts the flange *a* of the axle-box, and the section D an annular shoulder, *d*, against which fits the annular rim *e* upon the inner end 45 of the screw cap or nut B at its periphery.

Between the inner ends of the sections C D are located two clamping-plates, E F, which have annular recesses upon their outer sides near their periphery to receive the inner faces

or ends of the shells or sections C D. The clamping-plates E F near their outer periphery have 50 a series of bolt-holes, *f*, for receiving the bolts *g*, by which means the plates are securely held together by the employment of suitable screw-nuts, *h*, engaging with the screw-threaded ends 55 of the bolts. These bolt-holes *f* are so located with relation to the periphery of the plates E F that the heads of said bolts and the screw-nuts will come nearly in contact with the inner ends or rims of the sections C D, thereby 60 preventing them from unscrewing or getting loose.

The metal spokes G have ribbed sides *i*, and at their inner ends notches *k*, as shown in Fig. 4, said spokes fitting within radial grooves *l* 65 upon the inner faces of each of the clamping-plates E F, the notches *k* fitting over transverse bars *m* upon the inner surface or face of the plate E.

The annular recesses upon the outer sides of 70 the clamping-plates E F, which receive the inner faces or ends of the sections C D, are formed by casting said plates with annular rims *n*.

The grooves *l*, which clamp the spoke-ribs *i*, 75 sustain all the side and lateral pressure without bearing on the edges of the spoke at or near the periphery of the clamping-plates, the inner ends of each spoke being fitted to the periphery of the axle-box A, and firmly held 80 there by the notch *k* and its counterpart transverse bar *m*, which, when clamped together, form a lock and hold it firmly by means of the screw bolts and nuts.

The clamping-plates are so made that they 85 do not quite meet together, thereby allowing room for further tightening and clamping the ribs of the spokes by means of the bolts.

Having now fully described our invention, 90 what we claim as new, and desire to secure by Letters Patent, is—

1. In a metal hub having the usual shells or hollow metal sections, the combination, with the spoke formed with ribbed sides and a notch near its inner end, of two independent 95 clamping-plates located between said shells or hollow sections, one of said clamping-plates having on its inner face radiating grooves pro-

vided with transverse bars forming a counter to and fitting the notched spoke, substantially as and for the purpose specified.

2. In a metal wheel-hub, the combination, 5 with a ribbed and notched spoke, of clamping-plates having on their inner faces radial grooves corresponding with and fitting the ribbed spokes, said grooves being so formed as to bear against the ribs of the spoke and relieve the edges thereof from contact with said clamping-plates, substantially as and for the purpose set forth.

3. In a metal wheel-hub, the combination of

the ribbed spoke G, having notch k, clamping-plates E F, with their radial grooves l and 15 transverse bars m, hub shells or sections C D, axle-box A, cap or nut B, and clamping-bolts g, substantially as described.

In testimony that we claim the above we have hereunto subscribed our names in the 20 presence of two witnesses.

ROBERT W. DAVIS.
DANIEL DAVIS.
